UNITED STATES PATENT OFFICE.

WILLIAM C. BAKER, OF NEW YORK, N. Y.

CAR-HEATER.

SPECIFICATION forming part of Letters Patent No. 244,522, dated July 19, 1881.

Application filed April 20, 1881. (No model.)

To all whom it may concern:

Be it known that I, WILLIAM C. BAKER, of the city and State of New York, have invented an Improvement in Railway-Car Heaters, of which the following is a specification.

Car-heaters heretofore made are liable to warm some portion of the car more than the other portions. This is objectionable. In some instances the stove has been hung beneath the middle of the car and the heated air passed up into the car through flues. In this kind of heater the gases are very liable to penetrate into the car and the stove is liable to set the car on fire. Hot water has been employed by me for heating cars; but it required salt in solution or other material, to prevent freezing.

My present invention is for heating railway-cars with steam and for supporting the heater beneath the cars in such a manner that the water intervenes between the fire and the bottom of the car, and for preventing the injurious effects of frost, and for supplying an extra heating-surface near the four angles of the car or other portions requiring extra heat, and for preventing the waste of water from escaping steam, and for insuring a uniform fire that is proportioned to the atmospheric temperature.

In the drawings, Figure 1 is a vertical section of the heating apparatus transversely of the car. Fig. 2 is an elevation of the same and section of part of the car in smaller size.

The boiler that is used for supplying steam is made in the form of an inverted conoid, so that the water may freeze therein if the fire is allowed to go out without the expansion of the ice injuring said boiler, because the ice will simply slide up the inclined or conical sides and detach itself from the metal without the possibility of injury to the boiler; and I heat the car by steam-pipes that are at an inclination toward the boiler. Hence the water of condensation will always flow back into the boiler, and the steam will keep the parts of the pipes warm in which there is any water of condensation, and this will continue as the cooling operation goes on until the boiler alone remains warm. Hence when the temperature is reduced to the freezing-point the water will only be in the boiler and no portion of the apparatus will be injured. The inverted conoidal

bottom *a* of the boiler is of wrought-iron, and the top *b* is convex, the parts being united by rivets around the edges, as at *c*.

The case *d*, forming a fire-pot, is preferably made of cast-iron. So is also the ash-pit *d'*, which is bolted on below the case *d* so that in case of the car running off the track, the ash-pit and grate may be broken away from the fire-pot and boiler and lessen the risk of fire. This fire-pot and ash-pit can be easily replaced when broken or worn out without disturbing the boiler.

The bolts *e e*, which are employed to sustain the fire-pot, pass through ears at the bottom, and their upper ends enter the timbers of the car. It is preferable to surround this fire-pot with mineral wool or other non-conducting fire-proof material within a casing, *f*.

The grate *g* may be of any suitable character. I prefer a circular grate that may be acted upon by a "rattler" inserted into the ash-pit when the draft-door *k* is open. This draft-door *k* closes tightly against the inclined faces of the passage-way into the ash-pit, and when it is shut the fire will burn slowly, and the reverse when open. The draft-door is to be larger than the passage-way, so that wind cannot blow into the ash-pit when the door is partially open. This also prevents a suction action in the ash-pit when the car is moving with the draft-door to the rear.

The products of combustion pass off from the fire-chamber through lateral ascending flues *l* and vertical flues *m*. It is preferable to use flue-pipes that are oblong in section and covered with mineral wool or similar fire-proof material, and to pass these flues vertically and close to the sides of the car, and inside such car, and to cover them with a suitable ornamental casing. At the upper end there should be a cap or wind-guard. Two flues are preferably provided, one at each side of the car, to promote uniformity in the combustion in the fire-pot, and so that each flue may be small and less noticeable, and the radiation will be uniform on the insides of the car, and the appearance will be the same, and the heat economized; but one flue only may be used, if desired.

The fuel is introduced through the inclined hoppers *n n*, that are provided with doors that

close tightly, and the inclination should be such that the coal will shake down by the motion of the cars into the fire-chamber and constantly supply the fire as the coal is consumed.

- 5 These doors at the outer ends of the chutes may be held by a latch when closed, or they may be provided with a lever-crank or chain-connection, by which they can be opened or closed from the inside of the car when the train 10 is in motion, to admit air above the fire and regulate the intensity of the same.

There is upon the boiler a case, *o*, holding a steel or other flexible diaphragm, against which the steam-pressure acts, and the lever *p* is pivoted at *z*, and its other end is connected by a chain or rod to the draft-door *k*. This diaphragm and case are of ordinary construction, and the weight of the door is sustained by an adjustable spring, *s*; hence the door will be 15 open to admit the draft to the fire, except when the pressure exceeds the maximum pressure, when the diaphragm and lever will close the door. This spring *s* is to be adjusted by the attendant according to the atmospheric temperature. In very cold weather the draft-door can be adjusted so as not to close until a high pressure is attained in the boiler and in the radiators connected therewith, and in warmer weather the draft should be closed with a light 20 pressure of steam.

This heating apparatus is adapted to be self-regulating and to require attention but seldom; hence it is adapted to express-trains running long distances with few stoppages, as it 25 is best for the attendant to supply fuel and attend to the ashes when at the stopping-places. Provision, however, might be made for controlling the fire from within the car.

In order to supply water to the boiler, I 30 make use of the supply-pipe *q*, that is at the water-level and is provided with a screw-cap at the outer end. When this cap is removed water may be supplied through a movable funnel and lateral spout, and surplus water will 35 run out at the end of the same tube, so that too much cannot be introduced.

The radiators within the car may be of suitable character. I, however, employ rising branch pipes *t* from the central connection to 40 the boiler, and from these pipes *t* there are vertical pipes *t'* to the radiator-tubes *u*, that run along the cars close to the floor and at each side. The ends of the pipes are, however, to be highest, so that the water of condensation will 45 run back to the boiler, and there will be little or no waste of water. I incase the pipes with sheet-iron *v* and introduce sand or similar material between the steam-tube and the sheet-iron case, as in my Patent No. 209,793, so that 50

55 the steam-heat will be lessened in such portions of the car as may be desired, and in portions where but little heat is required mineral wool or other non-conducting material may be used in place of sand. At the ends of the radiator-pipes the casing *v* is discontinued, and the steam-pipe is increased in size, as at *w*, so that there will be an increase of heat from the 60

radiating-surface at the end portions of the car, which will prevent the difficulty heretofore arising in heating these portions of the 70 car and utilize the space that is now generally unoccupied. By this means the corners of the cars or any other desired portion may receive whatever proportion of heat is desired.

Air-valves of any approved construction are 75 to be provided on the radiator-pipes at the ends of the cars. Any portions of the steam-pipes that are below the car-floor should be incased in mineral wool or other non-conducting material.

With sleeping-cars it is not desirable to have much heat beneath the berths. By my improvement the sand-envelopes around the steam-pipes will materially lessen the heat, especially when the pressure is allowed to run 85 down at night, and the exposed radiating-surfaces at the ends of the car, or wherever they may be placed, will warm up the air in the car to the desired extent.

The vertical flues may be either wholly or 90 partially outside or inside the car, or they may pass up between the upright timbers of the framing, and the parts of the car adjacent to the flues may be of metal, or these metal parts 95 may form the flues.

The drawings represent the conoidal boiler with sides that are at an inclination of about ninety degrees to each other. This will insure the separation of the ice from the metal and cause the ice to rise as it expands without injuring the boiler; but it is to be understood that I am not limited to the angle represented or to any particular curvature given to the bottom of the boiler, so long as the breadth is sufficiently great in proportion to the depth to 100 prevent injury by frost.

I have spoken of the boiler as "conoidal." This term is to be understood as referring to the boiler having a sectional form substantially such as shown, in which the lower part 110 of the boiler approximates an inverted cone, the sides being inclined to each other and the parts more or less rounding, and it is necessary that the inclination of the sides to each be more than fifteen degrees, to prevent the 115 risk of injury by frost.

I am aware that kettles and various heating-vessels have been made with a rounding bottom, but the same were not adapted to the steam-heating pipes in a railway-car.

I am also aware that heaters have been placed below the floor of the car, and that water has been circulated through some of said heaters, but no provision was made for preventing injury from freezing.

I claim as my invention—

1. In a steam-heating apparatus for railway-cars, a boiler having a conoidal bottom, substantially as described, sufficiently broad in proportion to depth to prevent injury from the 130 water if it freezes, in combination with steam-radiating pipes arranged for the water of condensation to run back to the boiler, substantially as set forth.

2. In a steam-heating apparatus for railway-cars, a conoidal boiler, as described, and a fire-pot below the floor of the car, in combination with steam-radiating pipes within the car, placed at an inclination, so that the water of condensation runs back to the boiler, substantially as set forth.
3. The combination, in a steam-heating apparatus for cars, of a conoidal boiler, a fire-pot below the same, a flue passing off from the fire-pot, an inclined feeding-chute, a draft-door, and a diaphragm and lever to regulate the draft, substantially as set forth.
4. The combination, with the steam-generating boiler, as described, and furnace suspended below the car, of steam-radiating pipes placed at an inclination within the car, and a case surrounding a portion of the radiating-pipes, leaving such pipes exposed where the greatest heat is required, as set forth.
5. The combination, in a car-heater, of steam-pipes that are cased or inclosed in those portions of the car requiring little heat, and steam-pipes that present an enlarged area, and are not covered or cased in the portions of the car requiring greater heat, substantially as specified.
6. The combination, with the car-heating furnace suspended below the car, of an inclined feeding-chute and a door at the outer end for supplying fuel to the fire, and an inclined smoke-flue adjacent to the inclined feeding-chute, substantially as specified.

Signed by me this 12th day of April, A. D. 1881.

W. C. BAKER.
